UNITED STATES PATENT OFFICE.

ARTHUR HALFDAN MYHRE, OF TACOMA, WASHINGTON.

ENGRAVER'S RING-CLAMP.

1,157,120.

Specification of Letters Patent. Patented Oct. 19, 1915.

Application filed February 5, 1915. Serial No. 6,290.

To all whom it may concern:

Be it known that I, ARTHUR H. MYHRE, a citizen of the United States, residing at Tacoma, in the county of Pierce and State 5 of Washington, have invented a new and useful Improvement in Engravers' Ring-Clamps, of which the following is a specification.

This invention relates to a clamp designed especially for the purpose of holding circular objects, the device automatically bringing three spaced and separate contact points into position at equal distances from a common center.

10 The invention also consists of the novel features of construction hereinafter described, pointed out in the claim and shown in the accompanying drawings, in which:

Figure 1 is a section side elevation. Fig. 20 2 is a section on the line 2—2 of Fig. 1. Fig. 3 is a section on the line 3—3 of Fig. 2. Fig. 4 is a detail perspective view of one of the clamping members. Fig. 5 is a detail perspective view of a sector-shaped member, shown detached.

25 In the drawings 1 represents an engraver's block provided with the usual adjustable jaws 2, and the oppositely threaded operating screw 3. This block is of the ordinary construction and may be of any of the various types of such blocks which are in use and which are provided with jaws movable toward and away from each other.

30 The clamp which is the subject of this application comprises a circular two part base 4, one section of the base being provided with pins 5 which are adapted to enter suitable openings 6 formed in the other section of the base, said pins acting as guides.

35 40 Upon each base section is formed a vertical arm 7, which arm curves inwardly at its upper end as indicated at 8, the inner and under face being notched as shown most clearly in Figs. 4 and 5 in order to engage 45 the object to be clamped, such as a ring.

Adjacent the base each arm is provided with an inwardly and downwardly sloping edge cut-away upon each side so that said edge is V-shaped in cross section as indicated at 9. Adapted to work between the base sections 50 and between said arms is a sector 10, provided with a socket 11 upon its upper edge, said socket being adapted to receive any setting which may be carried between a ring 12 to be clamped. Upon opposite sides the 55 sector is provided with V-shape grooves 12 which are adapted to slide upon the surfaces 9 of the arms 7. Each base section is provided with two depending pins 13 adapted to enter suitable sockets formed in the jaws 2. 60

In operation the ring or other circular object to be held is placed in position upon the sector 10 and between the arms 7. The screw 3 is then rotated and the jaws 2 caused to move toward each other. This brings the 65 base sections toward each other, and this movement of the said sections will cause the sector to ride upwardly upon the surfaces 9. This upward movement is continued until the ends 8 of the arms 7 engage the ring, at 70 each point the ends of the arms and certain flanges 11^a formed upon the sector 10 adjacent the socket 11 will be positioned at equal distances from a common center. This centering and clamping movement is secured 75 by the one movement of the screw 3.

What I claim is:

The combination with the jaws of an engraver's block, a sectional base, means carried by each section of the base for securing 80 the same to one of said jaws, ring gripping arms carried respectively by said sections, and a ring engaging sector arranged between said arms and sections and movable with respect to them, said sector having a 85 setting ring socket.

ARTHUR HALFDAN MYHRE.
